UNITED STATES PATENT OFFICE

172,503

PORTABLE ELECTRIC HEATER

George Ross Johnson, Toronto, Ontario, Canada

Application December 18, 1953, Serial No. 28,124

Claims priority, application Canada
November 28, 1953

Term of patent 7 years

(Cl. D81—10)

To all whom it may concern:

Be it known that I, George Ross Johnson, a citizen of Canada, residing at Toronto, Province of Ontario, Canada, have invented a new, original, and ornamental Design for a Portable Electric Heater, of which the following is a specification, reference being had to the accompanying drawing forming a part thereof.

Fig. 1 is a perspective view of a portable electric heater, viewed from the front and from one side, showing my new design; and

Fig. 2 is another perspective view thereof, viewed from the rear and from the other side.

I claim:

The ornamental design for a portable electric heater, as shown.
